BY

E. C. Broome, *Sec.* ATTORNEYS.

UNITED STATES PATENT OFFICE.

DAVID W. BARTRAN, OF LAUREL, MISSISSIPPI.

HOE.

Application filed April 29, 1924. Serial No. 709,870.

To all whom it may concern:

Be it known that I, DAVID W. BARTRAN, a citizen of the United States, residing at Laurel, in the county of Jones and State of Mississippi, have invented certain new and useful Improvements in Hoes, of which the following is a specification, reference being had therein to the accompanying drawings.

This invention relates to hoes, and has 10 for its object the construction of a strong and durable hoe, which will give a maximum amount of service when in use.

Another object of the invention is the construction of a hoe that includes the blade 15 with a peculiarly pressed portion therein, producing a "saddle" for receiving the tubing or eye in which the handle is positioned.

The structure disclosed in this case is an improvement upon the structure disclosed in 20 my co-pending United States application, Serial No. 667,705, filed October 10, 1923, upon "hoes".

With the foregoing and other objects in view, my invention comprises certain novel 25 combinations, constructions and arrangements of parts as will be hereinafter described, illustrated in the accompanying drawings, and more particularly pointed out in the appended claim.

30 In the drawings:

Figure 1 is a perspective view of a blade and its integral parts, of a hoe constructed 35 in accordance with the present invention.

Figure 2 is a sectional view, taken on line 2—2, Fig. 1, and looking in the direction of the arrows.

Figure 3 is a sectional view through the blade and the tubing or eye, showing in dotted lines part of a handle assembled therewith.

40 Figure 4 is a fragmentary view, in elevation, of the blade looking at the inner end of the eye.

Referring to the drawings by numerals, 1 45 designates the blade which is provided with a brace or rib 2 welded in to hold the tubing or eye 3. This brace or rib 2 comprises a semi-conical portion 4, terminating at its upper end in the side portions 5—5, and 50 these side portions terminate in a bill por-

tion 6, into which semi-circular "saddle" or lip, constituted by the side portions 5 and bill 6, is seated the tubing or eye 3. This formation of the rib structure makes it easier to assemble the eye 3 with the blade, 55 requiring a minimum amount of welding, and at the same time a very durable structure is formed by reason of the side portions 5 and the bill 6 partly surrounding the eye, forming the "saddle", in which the eye is seated.

It is to be noted that the outer end of the eye 3 terminates in the same vertical plane with the outer face of the blade, when the 65 hoe is in use. The peculiar formation of the rib makes it simpler to assemble the eye, in that it is quickly seated in the "saddle" and then by reason of the bill portion 6 and the side portions 5 the welding operation is 70 quickly accomplished, whereby the eye is securely fastened to the blade. It is to be noted that I may braze the eye to the blade, as well as electrically weld the same.

While I have described the preferred embodiment of my invention, and have illustrated the same in the accompanying drawings, certain minor changes or alterations 75 may appear to one skilled in the art to which this invention relates, during the extensive manufacture of the same and I, therefore, 80 reserve the right to make such alterations or changes as shall fairly fall within the scope of the appended claim.

What I claim is:

A hoe comprising a blade having a portion intermediate its width and extending from its upper edge to a point intermediate its depth pressed rearwardly to provide a downwardly tapered saddle arcuate in cross section and having its upper portion provided with a rearwardly extending lip semi-circular in end elevation and having its end portions merging into the blade and walls of the saddle, and a handle receiving socket resting upon said lip and secured thereon with a portion extending forwardly from the lip over the saddle.

In testimony whereof I hereunto affix my signature.

DAVID W. BARTRAN.
